UNITED STATES PATENT OFFICE.

ANDREW BEARD, OF WOODLAWN, ALABAMA.

ROTARY ENGINE.

SPECIFICATION forming part of Letters Patent No. 478,271, dated July 5, 1892.

Application filed January 25, 1892. Serial No. 419,114. (No model.)

To all whom it may concern:

Be it known that I, ANDREW BEARD, a citizen of the United States, residing at Woodlawn, in the county of Jefferson and State of Alabama, have invented certain new and useful Improvements in Rotary Engines; and I do hereby declare the following to be a full, clear, and exact description of the invention, such as will enable others skilled in the art to which it appertains to make and use the same.

My invention relates to improvements in rotary engines, in which a piston head or heads are secured to a driving-shaft and revolve within an annular chamber, said piston head or heads being provided with pistons, which reciprocate in grooves formed in the heads, and the steam acting against the pistons causes the heads to rotate.

The object of my invention is to procure an efficient and cheap engine of the above-named construction which will be balanced in its running parts. The steam being admitted between annular walls on the inside of the head presses equally on all sides and does not force the head and shaft to one side of the bearing, as in the case of engines which take the steam on the outside of the head.

It is also an object of my invention to make an engine that can be easily reversed, which is accomplished by a simple appliance in the steam-chest, which is worked by a convenient hand-lever that admits steam to the cylinder, cuts steam off, and reverses the movement of the engine by different movements of the lever. I attain these objects by the construction and arrangement of the parts fully described and illustrated in the accompanying drawings, in which—

Figure 1 is a vertical sectional view of the engine with one side of the casing and part of the central partition removed to show the relative position of the heads and other internal appliances. Fig. 2 is a cross-sectional view through the line *a b*. Fig. 3 is an enlarged view of one of the heads. Fig. 4 is a cross-sectional view of one of the heads. Fig. 5 is an enlarged sectional plan view of the steam chest and valves. Fig. 6 is an enlarged side view of one of the pistons, and Fig. 7 a plan view of the same.

Similar letters refer to similar parts throughout the several views.

A is the base or bed of the engine to secure it to its foundation, consisting of two metal castings bolted securely to *B*, the central partition extending through the engine, dividing it into two parts. In this central partition are the steam-passages *Y Y* from the steam-chest and the steam-ports *H H*, admitting the steam to the heads *C C* at each side of the partition. On both sides of the partition, secured by screws between the ports, are abutments or steam-stops *Q Q*, that fit in the annular spaces of the head *C C* and are made steam-tight by the metallic packing-strips *R R*, set out by springs inserted in recesses underneath the strips. In the central partition *B* are metallic packing-rings *I I* to make a steam-joint to the annular walls of the heads *C C*. They are fitted in annular grooves and set out by springs inserted in recesses underneath them. In the central partition *B* is the passage *Z* for oil, to be fitted with any suitable oil-cup or lubricator, and by which the inner space of the heads can be kept filled with oil, all inside working parts thereby running in oil. At the bottom of the central partition are also passages *Z'*, to be fitted with a petcock to drain the inside of casing from condensation.

The piston-heads *C C* are secured on the main driving-shaft by splines or keys *W W* and with nuts *V V*, threaded on the shaft on the outside of the heads to force them against the central partition and to regulate the tension of the same. On the outer edge of the heads are the annular walls *O O*, and some distance inside are second annular walls *O' O'*, leaving a space *P P* between them, in which the steam is admitted through the ports *H H*. Each head is fitted with two pistons *T T*, working in grooves in the heads *C C*. These pistons are reciprocated by cams formed on their inner ends working against rollers *X X* on the ends of a shaft or studs *W W*, secured in the central partition *B*. On the lower half of the revolution of the heads the cams hold the pistons out against the outer walls of the heads *O O*. The pistons in this position form a stop against which the steam acts to rotate the heads. On the upper half of the revolution the cams withdraw the pistons *T T* from

the outer walls of the heads to let the exhaust steam escape and to allow the pistons to pass the steam-abutments Q Q. Secured to the central partition by this arrangement, one of the 5 pistons is always against the outer wall of the head, and the steam acting on it continues the engine in rotation.

The outer casings D D are recessed to inclose the heads and provided with flanges on 10 their outer edges and are secured together by bolting them through the central partition B. The casings do not touch the heads at any part thereof and are provided with hubs or extensions on the outer sides for 15 boxes or bearings for the shaft to work in, and on the outer ends are stuffing-boxes or glands E E. The main driving-shaft F passes through the bearings in the casings and the central partition and revolves freely, and secured firmly to the shaft are the heads C C, the 20 revolving of the heads by the steam communicating a similar motion to the shaft. Secured on the upper end of the central partition is the steam-chest and valves to control the starting, 25 stopping, and reversing of the engine. The steam enters at G into cylinder J and through the cross-passage N to the vertical passage Y, leading to the engine. Passing through the engine, it returns through the passage Y' to 30 the cross-passage N', to the cylinder J', and to the exhaust-opening I. The admission of steam, starting and stopping, and reversing of the engine are performed by the working of the plungers K K, working in cylinder J J' 35 and operated by rods L L and the hand-lever M. From the cylinder J J' are cross-passages N N', in which the vertical passages Y Y' to the engine are located. When the plungers K K are at opposite ends of the cylinder there 40 is only one of the passages to the engine open to the inlet-steam and the other one opens to the exhaust. When the plungers are in the center of the cylinders, steam is cut off, and when the plungers are reversed it reverses 45 the engine.

The operation of the engine is as follows: If the parts are in the position shown in the drawings, the steam will be admitted by the inlet-opening G to the cylinder J and cross- 50 passage N will enter the vertical passage Y and through the ports H H to the annular steam-space P P in the heads C C, and, pressing against the pistons T T, will cause the head and shaft to rotate when the pistons assume a horizontal position. The one in 55 advance draws away from the outer wall of the

head and allows the steam behind it to escape through the ports H H and steam-passage Y and the cross-passage N' to the cylinder J' and through the exhaust-opening I. By reversing the hand-lever to run the engine in the opposite direction the operation is the same, the inlet passages and ports becoming the exhaust and the exhaust passages and ports the inlet.

I am aware that prior to my invention rotary engines have been constructed with heads and reciprocating pistons, and I do not claim such invention, broadly; but

What I do claim, and desire to secure by Letters Patent, is—

1. In a rotary engine, the combination of the base with a central partition and heads on both sides, having casings on the outside recessed to inclose the heads and secured together by bolts passing through flanges on their outer edges and the central partition, said heads having pistons with cam-loops on their inner ends working over rollers on the ends of shafts or studs secured in the central partition to reciprocate the said pistons in grooves in the heads, substantially as described.

2. In a rotary engine, the combination of the base with a central partition and heads on both sides having casings on the outside recessed to inclose the heads and secured together by bolts passing through flanges on their outer edges and the central partition, and heads having pistons with cam-loops on their inner ends working over rollers on the ends of shafts or studs secured in the central partition to reciprocate the said pistons in grooves in the heads and having a steam-chest with reversing-lever and valves secured to the said central partition, with two steam-passages extending downwardly from the steam-chest through the central partition and opening on both sides and having abutments secured to both sides of the central partition between the ports, the said abutments filling the annular spaces in the piston-heads, substantially as described.

In testimony whereof I affix my signature in presence of two witnesses.

h/s
ANDREW X BEARD.
